UNITED STATES PATENT OFFICE.

JOSEPH B. ELKER, OF PITTSBURG, PENNSYLVANIA.

RAIL-JOINT.

SPECIFICATION forming part of Letters Patent No. 740,110, dated September 29, 1903.

Application filed March 13, 1903. Serial No. 147,586. (No model.)

To all whom it may concern:

Be it known that I, JOSEPH B. ELKER, a citizen of the United States of America, residing at Pittsburg, in the county of Allegheny and State of Pennsylvania, have invented certain new and useful Improvements in Rail-Joints, of which the following is a specification, reference being had therein to the accompanying drawings.

This invention relates to certain new and useful improvements in rail-joints; and the primary object of the invention is to construct a joint with means for carrying the wheels over the break or joint between the two rails in such a manner as to prevent hammering or battering of the ends of the rails, and the consequent smooth travel without jar.

My invention has for its further object to construct a joint which may be readily made and which will permit of the ready removal of the rails when it is desired to replace them or to remove for any other cause, and further, to construct a joint in which the rails will be permitted to have free expansion and contraction independently of the fish-plates.

Briefly described, the invention comprises a base or chair plate preferably made of a length to span two of the cross-ties and provided with notched lugs to receive the securing-spikes for fastening the same to the ties. This base or chair plate is provided with in-turned side flanges, and the fish-plates embracing the opposite sides of the rail have the outer edge of their flanges or base engaging underneath the side flanges, whereby the fish-plates are securely held at the base. One of the fish-plates is provided on its upper edge with a somewhat triangular-shaped block to fit in a cut-away portion provided therefor in the side of the rail-tread, which block forms a part of the rail-tread and receives the tread of the car-wheel. The fish-plates are bolted through the webs of the rails in the ordinary manner, the holes in the rail-web being larger than the diameter of the bolts, whereby to allow for expansion and contraction of the rails, and, if desired, one or both of the fish-plates may be provided with oblong apertures or openings to this same end.

All of the foregoing construction will be hereinafter more specifically described and then particularly pointed out in the appended

claims, and in describing the invention in detail reference will be had to the accompanying drawings, forming a part of this application, and wherein like numerals of reference will be employed for designating like parts throughout the different views of the drawings, in which—

Figure 1 is a detail perspective view of my improved joint in position. Fig. 2 is an end view of the joint with the rail in cross-section. Fig. 3 is a detail perspective view of the fish-plate, which carries the tread portion or block. Fig. 4 is a detail perspective view of a part of the rails as they are constructed to receive the tread portion or block carried by one of the fish-plates. Fig. 5 is a detail perspective view of the other fish-plate, and Fig. 6 is a transverse vertical sectional view of a modified form of construction of base or chair plate.

To put my invention into practice, I provide a base or chair plate 1, which is usually made of a length to span two cross-ties 2 and is constructed with notched lugs 3 on each side to receive spikes 4 for securing the chair-plate to the cross-ties 2. The base or chair plate is adapted to receive the rails therein and is provided along the upper edge of each side with in-turned side flanges 5, the space between the side flanges being sufficient to permit of the ready placing of the rail into the chair by slightly inclining the rail, so as to insert the one edge of the rail-base in under one of the side flanges, which will allow the opposite side of the rail-base to clear the opposite side flange of the chair. To this end the side flanges are slightly grooved, as seen at 6 in Fig. 2.

The space between the upper face of the rail-base 7 and the underneath face of the in-turned side flanges of the rail-chair is sufficient to permit of the engagement of the base 8 of the fish-plates therein, as seen in Figs. 1 and 2. The fish-plate 9 may be of the ordinary type generally employed, being provided with openings 10 to receive the securing-bolts 11. The fish-plate 12 is provided on its upper edge centrally of the length with a tread-block or portion 14, somewhat triangular in shape, which fits in the cut-away portion 15, provided therefor in the treads of the rails 16, at the adjacent ends thereof. The upper

face of this tread-block is flush with the treads of the rails, and consequently receives the tread of the car-wheels and carries the same over the break in the rails without jar.

5 As the rails will expand and contract to a greater degree or extent than the fish-plates, it is preferable to provide the fish-plate 12 with oblong holes 18. Each fish-plate on its inner face is made of standard type, whereby

10 the same will engage the underneath side of the rail-tread and the rail-base at the junction of the latter with the web, and thus support the tread of the rails under weight.

In Fig. 6 I employ the same style of fish-plates, but show a modified form of chair, which is made in two sections 17 19, each provided with the inturned side flange, as in the construction aforescribed. The sections or members 17 19 carry wedge-plates

20 21, respectively, which lie one on the other, the upper face of the plate 21 being on a horizontal plane to form a rest for the rail-base and the lower face of the plate 20 being on a horizontal plane and engaging with the

25 upper face of a base-plate 22, carried by the member 19, which base-plate at its free edge abuts against a flange 23 of the member 17 and to which it is secured by one or more bolts 24. This form, like the one aforescribed, may be provided with the notched lugs to receive the securing-spikes for fastening the chair to the cross-ties. By this construction I am enabled to lay the rails with a greater space between the ends thereof, since the tread-block will receive the tread of the wheel and carry the wheel over the joint, and hence I am permitted to employ a rail of greater length than ordinarily, and thus decrease the number of joints in the

40 track. Heretofore the practice of laying rails of twice the length of those ordinarily employed has been tried and abandoned owing to the large expansion of the rails requiring too great a space to be left between the ends.

45 It is to be noted that with a joint of my construction these rails of increased length may

be readily employed, as a space of sufficient size may be left between the ends of the rails, and the tread-block will carry the wheels over the joint without jar.

50

While I have herein shown and described the invention in detail as it is practiced by me, yet in the construction of the same it is evident that various slight changes may be made in the details of construction without departing from the general spirit of the invention.

55

Having fully described my invention, what I claim as new, and desire to secure by Letters Patent, is—

60

1. In a rail-joint, the combination with the rails having a cut-away portion in the outer face of the treads adjacent the ends thereof, of a chair-plate provided at each side with notched lugs to receive securing-spikes, in-turned curved flanges carried by said chair-plate at each upper side edge, fish-plates adapted to have their edges engaged underneath said in-turned side flanges, and a tread-block formed integral with one of said fish-plates to engage in the cut-away portion in the sides of the rail-treads, substantially as described.

65

2. In a rail-joint, the combination with the rails having cut-away portions in the side of the treads at the ends thereof, of a chair-plate formed in two members each having wedge-plates, each member having an in-turned curved side flange adapted to receive the base of the fish-plates, means for securing the two members of the chair together, and fish-plates fitting opposite sides of the rails, one of said fish-plates having a tread-block to engage in the cut-away portions in the sides of the treads of the rails, substantially as described.

70

In testimony whereof I affix my signature in the presence of two witnesses.

75

JOSEPH B. ELKER.
